UNITED STATES PATENT OFFICE.

WILLIAM A. LEWIS AND JOHN E. STEPHEN, OF ASHLAND, OKLAHOMA, ASSIGNEES OF
ONE-THIRD TO HARRY G. ROWLEY, OF STUART, OKLAHOMA.

RAIL TIE AND FASTENER.

1,021,936.

Specification of Letters Patent.

Patented Apr. 2, 1912.

Application filed October 17, 1911. Serial No. 655,201.

To all whom it may concern:

Be it known that we, WILLIAM A. LEWIS and JOHN E. STEPHEN, citizens of the United States, residing at Ashland, in the 5 county of Pittsburg, State of Oklahoma, have invented a new and useful Rail Tie and Fastener, of which the following is a specification.

This invention relates to metallic railway 10 ties and to means for fastening rails thereto, one of the objects of the invention being to provide an all metal tie which can be readily formed from heavy rolled metal, the tie having means integral therewith for engaging 15 the road-bed so as to prevent the tie from creeping.

A further object is to provide a metallic railway tie having integral rail seats or chairs, means being combined therewith for 20 adjustably engaging the base flanges of the rails so as to securely hold them against movement relative to the tie, said rail-engaging devices being adjustable so as to clamp tightly upon the rails.

25 With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

30 In the accompanying drawings the preferred form of the invention has been shown.

In said drawings;—Figure 1 is a plan view of a tie embodying the present improvements, the middle portion of the tie 40 being removed and the rail fastening devices only being shown at one end thereof, a portion of the other end of the tie being broken away. Fig. 2 is a central longitudinal section through the parts shown in

45 Fig. 1. Fig. 3 is a section on line A—B Fig. 1. Fig. 4 is a section on line C—D Fig. 1. Fig. 5 is a plan view of one of the jaws. Fig. 6 is an end elevation thereof. Fig. 7 is a side elevation thereof. Fig. 8 50 is a plan view of another one of the jaws. Fig. 9 is a front elevation thereof. Fig. 10 is a side elevation thereof.

55 Referring to the figures by characters of reference, 1 designates a channeled body formed by bending a heavy strip of metal

so as to form upstanding side flanges 2. Tongues 3 are struck downwardly from the bottom of the body and extend perpendicularly therefrom, these tongues being adapted to project into the road-bed so as to prevent the tie from creeping after it has once been placed in position. If desired, all of the metal may be removed from between the two tongues so as to thus reduce the cost of the tie and at the same time render it more 60 elastic than would be the case should the metal be retained within the tie bottom. Ears 4 are turned inwardly from the upper edges of the flanges 2 and form rail-supporting ledges or seats. Openings 5 are 65 formed within the flanges 2 at points below these ledges 4 and receive the ends of supporting rods 7, said rods being extended along the inner faces of the flanges 2 and parallel with the ledges 4, the ends of the 70 rods being upset, as indicated at 6, so as to prevent the rods from being accidentally withdrawn from the flanges. Notches 8 are formed in the upper edges of the flanges 75 at points between the two sets of ledges 4 80 and these notches receive tongues 9 projecting from the ends of cross strips 10 which bridge the space between the flanges 2. The strips have threaded openings 11 therein for the purpose hereinafter set forth. Openings 12 are formed within the flanges 2 between the rods 7 and the free ends of the tie body and these openings receive tongues 13 formed at the ends of cross strips 14 85 which bridge the space between the flanges 90 2 and have their upper edges in the same plane with the upper edges of the strips 10 and of the flanges 2. These strips 14 have openings 15 for the purpose hereinafter set forth.

95 The rods 7 hereinbefore described are designed to support the rail-engaging and fastening jaws to be used in connection with the tie. These jaws are arranged in pairs, and have been indicated by the letters E 100 and F, respectively. The fastener E has a base 16 having an integral plate 17 arched thereover, there being wings 18 extending laterally beyond the base 16 and designed to bear downwardly on the adjacent rod 7, 105 the ends of the base 16 forming shoulders 19 insertible between the rods 7. A rail-engaging jaw 20 projects from the plate 17 at one side thereof and notches 21 are formed within the other side of the plate, 110

The other fastener F is made up of a block 22 having a rail-engaging jaw 23 upstanding from one edge thereof, while spaced ears 24 extend from its other edge and are 5 adapted to project into the notches 21. This block has laterally extending wings 25 designed to bear downwardly on the rod 7. Clamping screws 26 extend through the threaded openings 15 and are adapted to 10 bear against the base plate 16, two of these screws being preferably employed for each fastening member E. A single clamping screw 27 extends through the opening 11 in each cross strip 10 and bears against the adjacent block 22. Each of these screws is 15 preferably provided with a lock nut such as indicated at 28.

When it is desired to fasten a rail to the tie, the screws 26 and 27 are loosened and 20 the fastening members E and F are moved apart a sufficient distance to permit the base flanges of a rail to be inserted between them and to rest upon the ledges 4. The screws 26 and 27 are then tightened, shifting the 25 members E and F toward each other until their jaws bind firmly upon the base flanges. It is to be understood that the wings 18 fit snugly between the ledges 4 and the rod 7 so as to prevent displacement of the fastening members E in either an upward or a 30 downward direction. Moreover, the jaws 20 fit snugly between and extend above the ledges so as to hold the fastening member E against lateral displacement. The same is 35 true also of the fasteners F, the jaws 23 thereof fitting snugly between the ledges 4 while the wings 25 fit snugly between the rods 7 and the ledges 4 so as to hold the fastening members F against displacement upwardly 40 or downwardly relative to the tie. After the fastening members have been tightly

clamped upon the rails between them, the screws 26 and 27 can be secured by means of lock nuts 28.

It will be apparent that the tie herein described can be very quickly and cheaply manufactured and by utilizing the rail fastening devices described, it becomes unnecessary to employ spikes or the like such as heretofore commonly used. 45 50

What is claimed is:—

1. The combination with a tie body having cross strips connected thereto, and rail-supporting ledges disposed between the strips, of supporting devices within the tie 55 body and under the ledges, rail-fastening members slidably mounted between the ledges and the supporting devices, said fastening members having interfitting portions, rail-engaging jaws upstanding from said 60 members and above the ledges, and means engaging the cross strips for shifting the members toward each other to bind their jaws upon a rail.

2. The combination with a tie body having rail-supporting ledges, of rail-engaging members extending under the ledges and having jaws projecting upwardly above said ledges, and means for supporting said members within the tie, each of said means including a length of material having laterally turned terminal portions secured with in the side of the tie body. 65 70

In testimony that we claim the foregoing 75 as our own, we have hereto affixed our signatures in the presence of two witnesses.

WILLIAM A. LEWIS.
JOHN E. STEPHEN.
